UNITED STATES PATENT OFFICE.

WALT NEWBROUGH, OF WILMINGTON, CALIFORNIA, ASSIGNOR OF ONE-HALF TO
GEORGE CHALKER, OF WILMINGTON, CALIFORNIA.

UNDERREAMER.

Application filed May 24, 1923. Serial No. 641,181.

To all whom it may concern:

Be it known that I, WALT NEWBROUGH, a citizen of the United States, and a resident of Wilmington, county of Los

5 Angeles, and State of California, have invented a new and useful Underreamer, of which the following is a specification.

The present invention relates to improvements in underreamers and has particular 10 reference to a means for enlarging a hole drilled into the earth underneath a casing introduced into the hole. To produce a tool of this character it is necessary to arrange the cutting blades in such a manner that 15 they will allow the tool to be lowered and raised through the casing and will become active only after the tool has reached its place below the casing. It is proposed to utilize for this purpose disk blades associated 20 with the tool in such a manner as to disappear when the tool is passed through the casing and to project outwardly when the tool is rotated after having reached its destination. A tool of this character is 25 rendered particularly effective when the blades are arranged at an angle to the axis of the casing so as to engage the wall under the casing in the same manner as a disk plow attacks the soil. It is proposed in the 30 present invention to provide an arrangement of this character in combination with means arranging of the easy insertion and removal of the disks.

The preferred form of the invention is 35 illustrated in the accompanying drawing in which Figure 1 shows a side view of my underreamer, Figure 2 side view of the same taken at right angles to the view shown in Figure 1, Figure 3 a detail view of a disk 40 cutter as viewed from the inside, Figure 4 a side view of the same, Figure 5 a top plan view of a removable portion of the retaining member of my tool, Figure 6 a side view of said portion, Figure 7 a section 45 through the same taken along line VII—VII of Figure 6, Figure 8 a longitudinal section through the whole device taken along line VIII—VIII of Figure 2, Figure 9 a detail view in side elevation of the retaining member, Figure 10 a sectional view taken along line X—X of Figure 1, and Figure 11 a bottom plan view of the retaining member shown in Figure 9. While I have shown 50 only the preferred form of the invention I 55 wish to have it understood that various

changes or modifications may be made within the scope of the claims hereto attached without departing from the spirit of the invention.

The blade retaining member (1) of my 60 tool is preferably made barrel shaped so as to easily pass upwardly and downwardly through a casing disposed in the hole of a well previously drilled. A cylindrical portion (2) formed integral therewith extends 65 upwardly and terminates in a threaded portion (3) adapted to be secured to a connecting member not shown in the drawing in any suitable manner. The reduced lower portion of the retaining member is also 70 threaded as shown (4). The barrel shaped portion (1) is provided with two oblong recesses (6) disposed in their general direction at an angle to the axis of the tool, the two 75 recesses lying in intersecting planes.

Each recess is formed to accommodate a disk cutter (5) such as shown in Figures 3 and 4 and has a knob (8) extending into the same with the knob pointing inwardly. The latter as far as its interior face is concerned 80 is spherical and adapted to be received in a corresponding central recess (9) in the disk (11). The spherical engagement allows of universal motion of the disk cutter 85 relative to its support but this motion is limited interiorly by the dimensions of the recess and exteriorly by the fact that a central embossment (12) projecting from the inner face of the disk cutter strikes that 90 portion of the wall defining the recess that lies opposite the knob (8). This particular portion is made removable to allow of the insertion and removal of the disk blade. It forms part of a central longitudinal slice 95 (13) shown in detail in Figures 5, 6 and 7 and shown as being removed in Figure 9. This slice, which when in place conforms exactly to the outlines of the adjacent parts of the blade retaining member is normally held 100 in place by means of a threaded sleeve (14) 105 engaging the threaded lower portion (4) of the tool.

The disks (11) are preferably formed with webs (16) for reinforcing purposes and water may be admitted into the chambers or 110 recesses (6) in which the disks work through the passage (17) communicating with the two recesses through two branches (18).

The manner of working my tool will be 115 readily understood from the foregoing de-

scription. The upper threaded end (3) of the tool is connected to a rod or shaft adapted to transmit rotary motion to the same from any suitable source of power. If 5 the tool is lowered through the casing the disk cutters which present their backs on the outside of the tool are made to disappear in the barrel shaped retaining member due to the engagement with the wall of the casing. 10 When a place below the casing has been reached the tool is rotated in the proper direction and the disk blades striking the wall of the hole will be swung outwardly on their respective pivots and will begin to scrape 15 the wall so as to enlarge the hole. Particular attention is called to the fact that the slanting position of the blades within the recesses causes the same to revolve on their own axes whereby a slicing action is produced rather than a mere scraping action and whereby the effectiveness of the tool is increased considerably. The disks are limited 20 in their outward motion by the embossment (12) previously referred to engaging 25 with the wall of the recess. As the hole below the casing has been enlarged the tool may be pulled upwardly and when the disk blades strike the bottom edge of the casing they are forced inwardly so as to disappear 30 within the retaining member. It should be understood that this latter operation is also assisted by the slanting position of the blades because the lower edge of the casing strikes the full rear face of the 35 blades instead of striking its edge only as it would if the blades were supported parallel to the axis of the tool.

If it is desired to remove the blades the sleeve (14) is screwed off and the central

slice (13) taken out whereupon the embossment (12) is free to swing about the pivot (8) until the disk is in a position that it may be removed.

I claim:

1. In an underreamer of the character described, a retaining member provided with a recess, a knob extending into the recess so as to point inwardly and a disc cutter having a recess in its back engaging with the knob for universal motion: 45
2. In an underreamer of the character described, a retaining member provided with a recess, a knob extending into the recess so as to point inwardly and a disc cutter having a recess in its back engaging with the knob 50 for universal motion, the disc being formed to limit the motion of the disc cutter. 55
3. In an underreamer of the character described, a retaining member provided with a slanting recess and an inwardly facing cutting element mounted in said recess with freedom of universal motion, with the walls of the recess holding the cutting element in a slanting position. 60
4. In an underreamer of the character described, a retaining member provided with a recess and an inwardly facing disc cutter mounted in said recess with limited freedom of universal motion. 65
5. In an underreamer of the character described, a retaining member provided with a slanting recess and an inwardly facing disc cutter mounted in said recess with freedom of universal motion, with the walls of the recess holding the disc cutter in a slanting 70 position. 75

WALT NEWBROUGH.
